(57) **CLAIM**

The ornamental design for a vehicle, toy, and/or replicas thereof, as shown and described.

DESCRIPTION

This application contains subject matter related to the following co-pending U.S. design patent applications:
Application Ser. No. 29/658,829, filed Aug. 3, 2018 and entitled “Radiator Grille for a Vehicle;” and
Application Ser. No. 29/624,709, filed Nov. 3, 2017 and entitled “Vehicle, Toy, and/or Replicas Thereof.”

FIG. 1 is a left, front perspective view of a vehicle, toy, and/or replicas thereof according to the design;

FIG. 2 is a left side view thereof;

FIG. 3 is a right side view thereof;

FIG. 4 is a left, rear perspective view thereof;

FIG. 5 is a front view thereof;

FIG. 6 is a rear view thereof; and,

FIG. 7 is a top view thereof.
